US00D836694S

(12) **United States Design Patent** (10) **Patent No.:** **US D836,694 S**
(45) **Date of Patent:** **** Dec. 25, 2018**

(54) **GOGGLE AUDIO-VISUAL ELECTRONIC HEADSET**

(71) Applicant: **Chris J. Katopis**, Washington, DC (US)

(72) Inventor: **Chris J. Katopis**, Washington, DC (US)

(**) Term: **15 Years**

(21) Appl. No.: **29/610,084**

(22) Filed: **Jul. 10, 2017**

(51) LOC (11) Cl. **16-06**

(52) U.S. Cl.

USPC **D16/131**

(58) **Field of Classification Search**

USPC D16/130, 132, 133, 134, 135, 202, 310,

D16/140; D14/137

CPC G02B 21/0004; G02B 21/22; G02B 21/24;

G02B 21/06

(57) **CLAIM**

The ornamental design for goggle audio-visual electronic headset, as shown and described.

DESCRIPTION

FIG. 1 is a rear elevated perspective view of a first embodiment of the goggle audio-visual electronic headset, showing my new design;

FIG. 2 is a front plan view, in an open position, thereof;

FIG. 3 is a rear view thereof;

FIG. 4 is a side view thereof;

FIG. 5 is the opposite side view thereof;

FIG. 6 is top view thereof;

FIG. 7 is bottom view thereof;

FIG. 8 is a front elevation view thereof, in a closed position; and,

FIG. 9 is a front elevation view thereof, in a closed position. In the drawings, the broken lines depict environmental subject matter only and form no part of the claimed design.

1 Claim, 9 Drawing Sheets
